[57] CLAIM

The ornamental design for a pencil cleaning disc and abrasive sheet package, as shown and described.

DESCRIPTION

FIG. 1 is a perspective view of a pencil cleaning disc and abrasive sheet package showing my new design;

FIG. 2 is a front elevational view;

FIG. 3 is a side elevational view, the opposite side being

a mirror image thereof;

FIG. 4 is a rear elevational view;

FIG. 5 is a top plan view;

FIG. 6 is a bottom plan view; and

FIG. 7 is a top perspective view in an open position.

*Fig. 1.**Fig. 2.**Fig. 3.**Fig. 4.**Fig. 5.**Fig. 6.**Fig. 7.*
